(57) **CLAIM**

I claim the ornamental design for a electric vehicle supply equipment, as shown and described.

DESCRIPTION

FIG. 1 is a front-right perspective view of an embodiment of an electric vehicle supply equipment;

FIG. 2 is a front view of the electric vehicle supply equipment of FIG. 1;

FIG. 3 is a rear view of the electric vehicle supply equipment of FIG. 1;

FIG. 4 is a left side view of the electric vehicle supply equipment of FIG. 1;

FIG. 5 is a right side view of the electric vehicle supply equipment of FIG. 1;

FIG. 6 is a top view of the electric vehicle supply equipment of FIG. 1; and,

FIG. 7 is a bottom view of the electric vehicle supply equipment of FIG. 1.

The broken lines shown in the drawings are included for the purpose of illustrating unclaimed portions of the electric vehicle supply equipment and form no part of the claimed design.
